GOLF BAG SUPPORT

Kenneth L. Roepke, 2430 W. 66th St., Indianapolis, Ind.
Filed Jan. 16, 1964, Ser. No. 338,101
2 Claims. (Cl. 248—96)

The present invention relates to a golf bag support.

When playing golf without a caddy, it is necessary to rest the bag of clubs on the ground while making a shot. If the player needs a different club than the one which he is holding, he must stoop down, pick up the bag and search through the clubs for the proper club. After the shot has been completed, the player must again stoop down to pick up the bag of clubs on the ground. Consequently, an important object of the present invention is to relieve the player from such bending and stooping.

Another object of the present invention is to provide an improved bag support adapted to hold the bag of clubs in a generally upright position while a player is making a shot, yet foldable out of the way while the player is carrying the bag between shots.

A further object of the present invention is to provide a device of the above type wherein the device is securely attached to the golf bag.

Related objects and advantages will become apparent as the description proceeds.

One embodiment of the invention might include a support device for a golf bag or the like comprising an elongated tubular member of a length substantially equal to a golf bag, a second tubular member telescoped within one end of said elongated member and having a hook on the distal end thereof, said hook curving back towards the proximal end of said second member and adapted to hook onto the edge of the golf bag at its open end, a screw threaded into the second tubular member adjacent said hook and projecting toward the distal end of the hook whereby said screw can be tightened against said bag to grip it against the distal end of said hook, means for adjustably securing said second tubular member relative to said elongated member, a third tubular member slidably received within the other end of said elongated tubular member, said third member having a cross bar secured to the end thereof within said elongated member, said elongated member having opposed elongated longitudinal slots through which said bar projects, a tension spring connected at one end to the other end of said elongated member and at the other end to said cross bar and normally projecting said third member to a position wherein said cross bar engages the ends of the slots toward said other end of said elongated member, a pair of legs each swingably connected to said elongated member between said slots and said one end of said elongated member, a pair of links each pivotally connected at one end to one of said legs and pivotally connected at the other end to said cross bar, a rigid C-shaped member fixed to said elongated member adjacent the other end thereof with its concave portion opening away from said elongated member and below said hook, a foot secured to said C-shaped member and flush with the other end of said elongated member, said foot and C-shaped member cradling the closed end of the golf bag, a strap associated with said C-shaped member and holding said bag against said C-shaped member and foot, said tension spring being of suitable strength to permit said third tubular member to telescope when the weight of the bag is on said foot and said third tubular member is against the ground.

The full nature of the invention will be understood from the accompanying drawings and the following description and claims.

FIG. 1 is a side elevation of the bag support of the present invention showing the support in operative position supporting a golf bag.

2

FIG. 2 is a front elevation of the structure of FIG. 1.

FIG. 3 is an enlarged longitudinal section taken along the line 3—3 of FIG. 2 in the direction of the arrows.

FIG. 4 is a side elevation of the bag support of FIGS. 5 1—3 and showing it in a different operating position.

FIG. 5 is an enlarged section taken along the line 5—5 of FIG. 1 in the direction of the arrows.

FIG. 6 is an enlarged section taken along the lines 6—6 of FIG. 1 in the direction of the arrows.

FIG. 7 is an enlarged section taken along the lines 7—7 of FIG. 4 in the direction of the arrows.

FIG. 8 is an enlarged perspective view of certain portions of the structure of FIG. 1.

For the purposes of promoting an understanding of the principles of the invention, reference will now be made to the embodiment illustrated in the drawing and specific language will be used to describe the same. It will nevertheless be understood that no limitation of the scope of the invention is thereby intended, such alterations and further modifications in the illustrated device, and such further applications of the principles of the invention as illustrated therein being contemplated as would normally occur to one skilled in the art to which the invention relates.

Referring more particularly to the drawings, there is illustrated a bag supporting device 10 including an elongated tubular member 11 having a length approximating the length of a short golf bag. Telescoped within the upper end 12 of the member 11 is a further tubular member 15 having a hook 16 formed at its distal end. The hook 16 is adapted to receive the edge 17 of the open end 18 of a golf bag 20 as illustrated in FIG. 1. A thumbscrew 21 is threaded received through the member 15 adjacent the hook 16 and projects toward the hook 16. The thumbscrew 21 may be tightened against the bag edge 17 to secure the bag to the device 10.

At the opposite end 25 of the tubular member 11, there is fixedly mounted a C-shaped member 26 which opens away from the tubular member 11 and is positioned below the hook 16. A foot 27 is fixed to the tubular member 11 flush with the lower end 25 of the tubular member 11. A strap 30 is threaded through suitable apertures 31 in the C-shaped member 26 and secures the lower end 32 of the golf bag within the cradle formed by the C-shaped member 26 and the foot 27. It can be appreciated that the assembly including members 26, 27 and strap 30 together with the hook 16 and screw 21 firmly attached the golf bag 20 to the elongated tubular member 11. It should be mentioned that the tubular member 15 is fixed in proper position to receive a golf bag of different size by a screw 35 threaded through the wall of the member 11 and engaging the member 15.

A bar 40 extends through the elongated member 11 centrally thereof. The bar 40 is fixed in position by a screw 41 which extends through an aperture 42 and threads into the bar 40. The bar 40 has reduced end portions 45 which pivotally receive legs 46. Nuts 47 are tightly threaded onto the reduced portions 45 and retain legs 46 thereon.

The elongated tubular member 11 is provided with opposed slots 50 through which project the opposite ends of a bar 51. The bar 51 is secured to the upper end of a tubular member 52 telescoped within the lower end 25 of the tubular member 11. The bar 51 has reduced end portions 55 which pivotally receive one end 56 of links 57. The other end of each link 57 is pivotally secured to one of the legs 46. The bar 51 has slots 49 which are located at the slots 50 and receive the walls of member 11 at those slots to resist twisting of the bar 51. Thus, the bar 51, which has a curved concave shape, cups the golf bag and prevents its sliding to one side or the other.

A tension spring 60 is connected between the lower end 25 of the tubular member 11 and the cross bar 51, said

spring extending through a slot 53 in the wall of the tubular member 52. The tension spring 60 normally projects the member 52 to the position illustrated in FIG. 4 wherein the cross bar 51 is engaging the lower end 61 of each slot 59. This position of the structure is illustrated in FIG. 4 and is the position that the apparatus assumes when the player lifts the bag away from the ground. When the spring 60 projects the member 52, the legs 46 are retracted against the sides of the member 11 by the movement of the cross bar 51 and the links 57 with the cross bar. Of course, the structure 10 is easily carried on the golfer's bag when the legs are retracted as in FIG. 4.

When it is desired to set up the golf bag in the position of FIGS. 1 and 2, the player rests the golf bag and structure 10 on the ground with the lower end of the member 52 engaging the ground. The weight of the golf bag is sufficient to depress the member 52 into the tubular member 11. The movement of the member 52 into the member 11 causes the links 57 to swing the legs 46 away from the member 11 to the position of FIGS. 1 and 2. The complete structure may then be tilted over against the legs 46 to support the golf bag in the generally upright position of FIGS. 1 and 2. It should be mentioned that the legs 46 are bent at the connection of the links 57 to the legs and in such a manner that the distal ends of the legs extend inwardly to prevent the legs locking in the inward position.

It will be evident from the above description that the improved bag support of the present invention is adapted to hold the bag of clubs in an upright position while the player is making a shot, yet is automatically foldable out of the way while the player is carrying the bag between shots. It will also be evident that the bag support of the present invention incorporates highly efficient means for securing the golf bag to the bag support.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention and the scope of the claims are also desired to be protected.

The invention claimed is:

1. A support device for a golf bag comprising an elongated tubular member of a length substantially equal to a golf bag, a second tubular member fixedly telescoped within one end of said elongated member and having a hook on the distal end thereof, said hook curving back towards the proximal end of said second member and adapted to hook onto the edge of a golf bag at its open end, a third tubular member slidably received within the other end of said elongated tubular member, said third member having a cross bar secured to the end thereof within said elongated member, said elongated member having opposed elongated longitudinal slots through which said bar projects, a tension spring connected at one end to the other end of said elongated member and at the other end to said cross bar and normally projecting said third member to a position wherein said cross bar engages the ends of the slots toward said other end of said elongated member, said tension spring being received within said elongated tubular member and third member, said third member having a longitudinally extending slot through which tension spring extends, a pair of legs each swingably connected to said elongated member between said slots and said one end of said elongated member, a pair of links each pivotally connected at one end to one of said legs and

5 pivotally connected at the other end to said cross bar, a rigid C-shaped member fixed to said elongated member adjacent the other end thereof and having its concave portion opening away from said elongated member below said hook, a foot secured to said C-shaped member and flush with the other end of said elongated member, said foot and C-shaped member adapted to cradle the closed end of a golf bag, and a strap associated with said C-shaped member and adapted to hold a bag against said C-shaped member and foot, said cross bar being curved into a concave shape which opens in the same direction as said C-shaped member for reception of a golf bag, said cross bar having oppositely opening slots at said element longitudinal slots and receiving the walls of said element at said element longitudinal slots to resist rotation of said cross bar and maintain it in a position opening in the same direction as said C-shaped member.

2. A support device for a golf bag or the like comprising an elongated element of a length substantially equal to a golf bag and having a hook on the upper end thereof, said hook curving back towards the elongated element and adapted to hook onto the edge of a golf bag at its open end, a tubular member slidably received within the lower end of said elongated tubular element, said tubular member having a cross bar secured to the end thereof within said elongated element, said elongated element having opposed elongated longitudinal slots through which said bar projects, a tension spring connected at one end to the lower end of said elongated element and at the other end to said cross bar and normally projecting said tubular member to a position wherein said cross bar engages the lower ends of the slots, a pair of legs each swingably connected to said elongated member between said slots and said one end of said elongated member, a pair of links each pivotally connected at one end to one of said legs and pivotally connected at the other end to said cross bar, a rigid C-shaped member fixed to said elongated element adjacent the lower end thereof and having its concave portion opening away from said elongated member below said hook, a foot secured to said C-shaped member and flush with the lower end of said elongated element, said foot and C-shaped member adapted to receive the closed end of a golf bag, and a strap associated with said C-shaped member for holding a bag against said C-shaped member and foot, said cross bar being curved into a concave shape which opens in the same direction as said C-shaped member for reception of a golf bag, said cross bar having oppositely opening slots at said element longitudinal slots and receiving the walls of said element at said element longitudinal slots to resist rotation of said cross bar and maintain it in a position opening in the same direction as said C-shaped member, said legs being curved inwardly toward said element at the respective link-leg connections.
